ATTORNEYS.

UNITED STATES PATENT OFFICE.

GEORGE HASSIG, OF PHILADELPHIA, PENNSYLVANIA.

TOY.

Application filed February 6, 1923, Serial No. 617,289. Renewed July 24, 1925.

To all whom it may concern:

Be it known that I, GEORGE HASSIG, a citizen of the United States, residing at Philadelphia, in the county of Philadelphia and

5 State of Pennsylvania, have invented certain new and useful Improvements in Toys, of which the following is a specification, reference being had therein to the accompanying drawings.

10 This invention relates to a mechanical toy, and the object of the invention is the construction of a simple and efficient amusement device involving a figure device and a firing device of a peculiar nature, which are 15 simultaneously operated for producing entertainment or amusement for the operator.

Another object of the invention is the construction of a toy comprising a peculiarly formed firing device and a figure device 20 each connected to work in unison so that the desired amusing effect will be produced.

With these and other objects in view, my invention comprises certain novel combinations, constructions and arrangements of 25 parts as will be hereinafter described, illustrated in the accompanying drawings, and more particularly pointed out in the appended claims.

In the drawings:

30 Figure 1 is a view in side elevation of a mechanical toy constructed in accordance with the present invention, while

Figure 2 is a top plan view of the same.

Figure 3 is a fragmentary, longitudinal, 35 sectional view of the toy.

Figure 4 is a bottom plan view of the toy.

Figure 5 is a fragmentary, perspective view of the firing apparatus.

40 Figure 6 is a fragmentary, sectional view of the toy, showing particularly the figure device.

Referring to the drawings by numerals, 1 designates a platform supported by legs 2, 45 A figure device 3 is mounted upon one end of the platform 1, and at the opposite end is mounted a firing device 4.

The figure device comprises a rotatable table 5 connected to vertical shaft 6, and on 50 the lower end of shaft 6, under platform 1, is a belt wheel 7; the belt wheel 7 is securely fastened to shaft 6, so that rotation of the wheel will cause the table 5 to be likewise rotated. Hinged figures 8 are mounted upon 55 the table 5 for the purpose of being forced or thrown inwardly when a shell 9 hits the

same. A shield 10 is placed around the end of platform 1 contiguous to the firing device so that the projectiles or shells 9 are ordinarily prevented from falling off the platform after they have struck a figure 8, or if they miss the figure; at least the shield 10 in most instances, prevents the shells from passing beyond the end of platform 1.

The shells 9 are mounted in apertures 11, and each is of a cylindrical shape; each shell is provided with an annular groove 12, into which projects the inner edges of the two guide plates 13 of the firing device 4. The shells 9 pass down in slot 14 of the body 15 dropping below the guide plates 13 and resting upon the sight piece 16. These plates 13 will serve to guide the shell into the proper position but since the shell passes below their lower ends, they will not interfere with the forward movement of the shell when fired. The inner end of the shell bears against the spring lip 17 of stop plate 18, which stop plate is secured to the end of body 15, Fig. 3. The lip 17 serves as a 75 yieldable bumper to limit rearward movement of the shell and prevent wedging of the shell when put in place. A guide bracket 19 is placed contiguous to the rear end of body 15, and slidably mounted under 80 guide bracket 19 is a sliding plunger 20; plunger 20 is adapted to strike the rear end of each of the shells 9 to throw it forward against a hinged figure 8. A swinging arm 21 extends downwardly beyond the lower 85 face of platform 1, and this arm is provided with a pair of outwardly extending apertured ears 22. The arm 21 is also provided with an upwardly extending tongue 23, which tongue 23 projects through slot 24 (Fig. 3) in the sliding plunger 20. A pair 90 of brackets 25 are fastened to the rear end of platform 1; a bolt 26 extends through brackets 25 and through ears 22, pivotally 95 mounting the swinging arm upon the rear end of platform 1.

Journaled upon the two legs at the rear end of the platform is a shaft 27, which shaft is provided at one end with hand wheel 28, for rotating the shaft. A belt 100 wheel 29 is fixedly secured to the shaft near its middle, and wheel 29 is provided with a hub 30 and with fingers 31. Fingers 31 are adapted to engage the lower end of swinging arm 21 for causing the arm to swing or draw rearwardly upon plunger 20 and upon 110 the finger leaving the arm 21, through the

action of bowed spring 32, fastened, at 33, to the platform 1, the plunger is forced forwardly with great rapidity and of sufficient strength to strike the shell, resting upon body 15 and cause said shell to be thrown forwardly and with sufficient force, engaging a figure 8 to throw it down upon table 5. A suitable belt 34 is positioned upon belt wheels 7 and 29, so that when the operator 10 turns hand wheel 28 simultaneously with the firing of the firing device 4 a figure 8 will be placed in alignment with the sight piece 16 so that as a rule a shell 9, projected from the firing device will hit a hinged figure and 15 cause the same to be thrown inwardly and down upon the table, in an unhinged position.

It is, therefore, to be understood that I have produced a mechanical toy with a peculiarly constructed firing device working in timed relation with a rotatable table, carrying movable figures so that each time the firing device is operated, for throwing a shell toward the rotatable table, a hinged 25 figure will be placed in alignment with the firing device so that the hinged figure may be struck by the shell and thrown downwardly.

The bowed spring 32 has its free end 30 placed directly under the outer end of plunger 20, and above the apertured ears 22 (Figs. 2 and 3). This spring exerts a great amount of pressure, causing the sliding plunger to move rapidly forwardly, with 35 great force, sufficient to throw the shell against a figure and cause the same to hinge or swing over upon the table.

While I have described the preferred embodiment of my invention, and have illustrated the same in the accompanying drawings, certain minor changes or alterations 40 may appear to one skilled in the art to which this invention relates, during the extensive manufacture of the same and I, therefore, 45 reserve the right to make such alterations or changes as shall fairly fall within the scope of the appended claims.

What I claim is:

1. In a device of the class described, the 50 combination with a platform, of a rotatable table provided with figures on said platform, a belt wheel, means connecting said belt wheel to said rotatable table, a firing device on said platform including projectile ejecting means spring pressed in an ejecting direction, a second belt wheel contiguous to said firing device, said second belt wheel provided with a hub and with fingers for engaging the projectile ejecting means and 55 moving the same against the action of its

spring and then releasing the ejecting means during rotation of the second belt wheel, and a belt mounted upon said belt wheels.

2. In a device of the class described, the combination with a platform, and a target device on said platform, of a firing device on said platform for ejecting projectiles towards said figure device, said firing device comprising a slotted body provided at its forward end with guide plates and with a sight piece and at its opposite end with a stop plate for limiting rearward movement of a projectile passed downwardly in the slotted body below the lower ends of the guide plates with its forward end resting upon said sight piece, and shell ejecting means contiguous to said stop plate and one end of said slotted body.

3. In a device of the class described, the combination with a platform, and a target device on said platform, of a firing device on said platform for ejecting projectiles towards said figure device, said firing device comprising a shell-supporting body, a bracket on the platform contiguous to one end of said body, a sliding plunger under said bracket having its inner end contiguous to said body, a swinging arm provided with apertured ears, a pivot pin carried by said body and passing through said ears to pivotally mount said arm upon said platform, said swinging arm provided with a tongue extending through said plunger, spring means yieldably holding said arm against swinging movement and with the plunger projected 95 forwardly, and means for moving said swinging arm to cause the plunger to be moved rearwardly under the bracket and then releasing the arm to permit said spring means to move the plunger forwardly and 100 eject the shell towards said target.

4. In a device of the class described, the combination with a platform, and a target device on said platform, of a firing device on said platform, said firing device comprising a slotted shell-receiving body, a stop plate secured to one end of said body, said stop plate provided with an outwardly bent spring lip registering with the slot in the body for engagement by the rear end of a projectile placed in the slotted body, a sliding plunger under said lip, spring means for forcing said plunger inwardly, and means for drawing the plunger outwardly against the action of its spring and then release the plunger.

In testimony whereof I hereunto affix my signature.

GEORGE HASSIG.
